US0D1100399S

(12) **United States Design Patent** (10) **Patent No.:** **US D1,100,399 S**
(45) **Date of Patent:** **** Oct. 28, 2025**

(54) **COATING MATERIAL CONTAINER**

(71) Applicant: **SWIMC LLC**, Cleveland, OH (US)

(72) Inventors: **Michael C. Lambertson, Jr.**, Aurora, OH (US); **Joshua R. Robertson**, North Ridgeville, OH (US)

(73) Assignee: **SWIMC LLC**, Cleveland, OH (US)

(***) Term: **15 Years**

(21) Appl. No.: **29/903,921**

(22) Filed: **Sep. 28, 2023**

Related U.S. Application Data

(63) Continuation of application No. 29/883,467, filed on Jan. 30, 2023, now Pat. No. Des. 1,005,634, which is a continuation of application No. 29/764,268, filed on Dec. 29, 2020, now Pat. No. Des. 980,571, which is a continuation of application No. 29/682,054, filed on Mar. 1, 2019, now Pat. No. Des. 908,999.

CLAIM

The ornamental design for a coating material container as shown and described.

DESCRIPTION

FIG. 1 is a perspective view of a coating material container showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines illustrate portions of the coating material container that form no part of the claimed design.

1 Claim, 7 Drawing Sheets
